UNITED STATES PATENT OFFICE.

RICHARD D. GALLAGHER, OF CHICAGO, ILLINOIS, ASSIGNOR TO ROOS FOUNDRIES, INC., OF CHICAGO, ILLINOIS, A CORPORATION OF ILLINOIS.

PORTABLE CAR STOP OR CHOCK.

Application filed March 20, 1922. Serial No. 545,062.

To all whom it may concern:

Be it known that I, RICHARD D. GALLAGHER, a citizen of the United States, residing in the city of Chicago, in the county 5 of Cook and State of Illinois, have invented certain new and useful Improvements in Portable Car Stops or Chocks, of which the following is a specification.

My invention relates to portable car stops 10 such as are employed on railways to fix the position of a car whenever it becomes necessary to make temporary repairs, and also adapted to be employed for limiting the movement of cars on tracks as occasion demands.

My invention has particular reference to a portable stop which is self contained and which is secured to a track by clamping, and which has no loose or separate parts to be 20 come lost.

An object of my invention is to provide a car stop or chock which may be readily clamped in position on a rail and which will effectively serve its purpose.

Another object of the invention is to provide a stop or chock to prevent movement of cars and which stop is self contained and which may be easily and quickly applied and released.

A further object of the invention is to provide a temporary car stop or chock which is self contained and which has a pair of tong-like clamps for engaging each side of a rail and having cams for actuating the clamps.

A further object of the invention is to provide a car stop or chock which is self contained and which has quick acting fingers for gripping a rail.

A still further object of the invention is to improve car stops or chocks for generally successful commercial use.

In carrying out the preferred embodiment of my invention, I employ what I term a body member which is made preferably of cast metal and which has a curved portion serving as a stop for a wheel, a longer under side for resting on a rail head and laterally depending flanges for preventing lateral displacement of the body on the rail and fingers adapted to grip each side of the web of the rail and means for actuating the fingers.

The above recited and other objects of my invention will be apparent from the follow-

ing description and drawings and will be particularly pointed out in the appended claims.

In the drawings:

Figure 1 is a side elevation of the preferred embodiment of my invention showing the parts in unlocked position.

Figure 2 is an end elevation looking at the right hand end of Figure 1.

Figure 3 is a vertical section taken on the line 3—3 of Figure 1, showing the fingers in gripping position.

Figure 4 is a view similar to Figure 3 showing the position assumed by the parts when the fingers have been raised against the under side of the rail head.

Figure 5 is a front elevation of the three part cam I employ for actuating the gripping levers.

Figure 6 is a side elevation of the cam of Figure 5 looking at the left hand side thereof.

Figure 7 is an elevation of the cam looking at the right hand side of Figure 5.

Figure 8 is a side elevation of one of the gripping levers of my invention.

Figure 9 is an end elevation of Figure 8.

Figure 10 is a view similar to Figure 8 showing the reverse side of the arm.

Figure 11 is a view of the cam similar to that shown in Figure 6 arranged schematically for illustrating the action of the cam on the arms.

Figure 12 is an elevational view partly in section, showing the position of the cam member after the same has been turned for the purpose of moving the lever against the rail web, and

Figure 13 is a view similar to Figure 12 showing the position of the cam and the lever arm after the arm has been raised against the under side of the head of the rail.

In the drawings, 20 represents a portion of a standard T rail in connection with which my invention is illustrated.

The stop comprises a body A, formed preferably as a casting and having a substantial flat bottom 21 for resting on the head of the rail 20, a portion of the stop is curved as at 22 to conform to the shape of the car wheel and this portion serves as a stop or abutment for a car. The body A has a cut out portion 23 disposed as shown in the drawings and a front portion 24 for

resting on the rail. Near the bottom of the body member A and depending therefrom are lugs 25 arranged to straddle the head of the rail for preventing lateral displacement of the stop thereon. Extending through suitably disposed apertures 26 arranged in the body A is a shaft 27 carrying a handle 28 having a hub 29 for receiving the shaft and which hub is secured thereon by means of the nut 30, or other similar securing device. The handle 28 is operable exteriorly of the body portion of the stop. The shaft 27 is shown as square in section as may be seen in other figures of the drawings, also the opening through the hub 29 is square for the purpose of preventing turning of the handle on the shaft. The shaft 27 carries the cam member B shown in Figure 5, the cam having a square opening 31 therethrough for receiving the shaft. Below the shaft 27 is a second bolt or pivotal member 32 passing through suitably arranged apertures 33 in the body member A. This bolt is circular in section and is retained in position by a nut 34 and a head 35. This bolt is parallel to and in the same plane of the shaft 27, both the shaft 27 and the bolt 32 lying in the same vertical plane coincident with or parallel to the rail 20. Mounted on the bolt 32 as a pivot are the lever arms C and D. These arms are exact duplicates in every respect but are referred to by two reference characters for the purpose of clearness in describing the construction and operation of the device. Each of these levers has an elongated opening 36 through which the pivot bolt 32 passes. The arms are made as shown in the drawings having lower portions or feet 37 which clamp against the web of the rail 20, as will be more fully described hereinafter. The arms have cut away or inclined portions 38 to enable the same to clear the head of the rail. The upper ends of the arms C and D are formed with two cam surfaces, one surface designated by the reference character 39 and the other part the reference character 40. The same cams in Figure 10, that is in lever D, are indicated as 39' and 40', respectively, although in shape and arrangement these are exactly the same as cams 39 and 40. By reference to the drawings it will be noted that cams 39 and 39' consist of openings passing through the arms laterally and which cams have high points 41 and 41', respectively. The cams 40 and 40' appear as ledges, the depths of which are less than the width of the arms, as will be seen by reference to Figure 9.

Referring to Figure 5, the cam B, as before stated, consists of three parts designated respectively as E, F and G. The contour of the cam E and the cam G is shown in Figures 6 and 11, while the contour of the cam F and the cam G is shown in Figure 7. The outlines of the cams E and F are exactly the same, but these cams are arranged in different angular positions about the axis of the cam member in order to act on the high point 41 and 41' of the cam 39 and 39' for simultaneously moving the same, as will now be more fully described.

In assembling the stop of my invention the cam member B is secured in any suitable manner on the shaft 27, and the arms C and D mounted on the common pivot 32 in cross-wise relation occupying the positions shown in Figures 2, 3 and 4 of the drawings and arranged to act like scissors. The upper ends of these levers are arranged with the cam 39 cooperating with the cam E of the cam member B and the cam 39' of the lever D with the cam F, while the cam G is positioned to cooperate with cams 40 and 40' on the lever arms. The parts having thus been arranged, the shafts 27 and 32 are fastened in position by means of the nuts 30 and 34 and head 35; the handle 28 having been applied as shown, the cams and the several parts are arranged so that when the handle 28 is in the position shown in Figure 1 and Figure 2 the levers are in separated or non-gripping position. When in this position the square shaft 27 is as shown in Figure 2 and Figures 6, 7 and 11, the normal position of the cams corresponding to this position of the shaft.

The stop now being applied to a rail 20 with the lugs 25 disposed to properly position the stop thereon; the handle is then grasped and turned in clockwise direction as viewed in Figures 2, 3 and 4 for effecting clamping of the rail by the levers C and D.

Referring to Figures 11, 12 and 13, it is believed that the action of the cams E and G against the cams 39 and 40 of the lever C will be clear. Figure 11 has been laid off in a schematic manner by lines disposed at equal angles and where these lines have cut the surface of the cam G, the points have been indicated in the manner shown. The position of the cams E and G in Figure 11 is, as before explained, the normal or inoperative position of the same. The levers are so mounted that the high point 41 of the lever C is always against the surface of the cam E while the cam 40 is always against the cam G. Consequently, when the handle is turned in clockwise direction, the cam E, as will be readily apparent, tends to move the high point 41 of the cam 39 to the left, which swings the lever arm C about the pivot 32 in the manner as one of the members of a scissors is moved. The handle is continued in clockwise direction until the foot 37 of the lever is brought against the web of the rail 40. When this occurs the cam E has moved to the position shown in Figure 12. While the cam E has been moving the upper end

of the lever C to the left by reason of the cooperation of the cams E and 39, the cam G has acted to raise the arm C by reason of its engagement with the cam 40 of said arm, 5 so that when the foot 37 of the arm is brought into contact with the web of the rail, the arm or lever will have been raised slightly on the pivot 32 occupying the position shown in Figure 12. A slight movement 10 of the handle in the clockwise direction will move the cams E and G into such position with respect to the cam 39 and 40 that the lever arm C will be held against displacement with respect to the rails. In 15 other words the cams have passed the high point of the same and in order to permit disengagement of the foot 37 of the lever C with the rail, manual operation of the cams in opposite direction is essential. The position 20 of the arm C with respect to the rail after the handle 28 has been stopped in its movement is indicated in Figure 13 of the drawings where it is apparent the foot 37 is in contact not only with the web of the 25 rail but also with the under side of the head, thus causing a tight gripping of the levers or arms C and D with the rail and firmly positioning the rail stop thereon.

I have described the operation in the preceding paragraph of the arm C only. The arm D is moved in exactly the same manner under influence of cams F and G but in the opposite direction, so that when the handle has moved the shaft 27 to the position 35 shown in Figure 13, the clamping arms C and D will be in engagement with the rail 20 in the manner shown in Figure 4 and the arm 28 will be substantially in the position as it appears there.

40 It will be noted that I effect clamping engagement by means of a pair of arms disposed in scissor-like manner on a common pivot and which are influenced by a three-part cam, two of the three cams acting separately 45 with respect to the two levers and the third cam acting in common with the two levers. By this arrangement I am enabled to securely clamp the rail and firmly hold the stop thereon. The last final squeezing movement 50 of the handle I have found to be sufficient to securely fasten the stop against displacement by a car. As a means of locking the handle 27 to the body A after the stop has been clamped to a rail, I provide the 55 handle with an apertured lug 42 and the front end 24 of the body A with an aperture 43, so that a chain may be passed through these apertures and secured by a padlock, thus preventing movement of the handle 28 60 in counter clockwise direction to unlock the stop and permitting unauthorized removal of the same.

While I have described more or less precisely the details of construction of my invention, I do not wish to be understood as

limiting myself thereto, as I contemplate changes in the form and proportion of parts and the substitution of equivalents as circumstances may suggest or render expedient, without departing from the spirit of my 70 invention.

I claim:

1. A rail stop comprising a body adapted to rest on a rail head, a pair of grippers mounted scissors fashion within said body 75 and depending therefrom, and means operable to cause said grippers to pinch a rail under certain conditions.

2. A rail stop comprising a body adapted to rest on a rail head, pincer-like grippers 80 mounted therein for angular and longitudinal movement, and means operable exteriorly of said body for causing said grippers to pinch a rail.

3. A rail stop comprising a body adapted 85 to rest on a rail head, pincers-like grippers mounted therein for angular and longitudinal movement, and cams operable exteriorly of said body for causing said grippers to pinch a rail.

4. A car stop including a body member adapted to rest on a rail head, grippers mounted therein adapted for scissors like action and projecting below the bottom of said body, cams cooperating with the inner 95 ends of said grippers for producing a scissors movement thereof, and means operable exteriorly of said body for actuating said cams.

5. A car stop including a body member 100 adapted to rest on a rail head, grippers mounted therein adapted for scissors like action and projecting below the bottom of said body, cams cooperating with the inner ends of said grippers for producing a scissors like movement thereof, means operable exteriorly of said body for actuating said cams, and means for locking said last mentioned means to prevent unauthorized removal of said stop.

6. A car stop comprising a body adapted 110 to rest on a rail and having a portion thereof curved to form a wheel abutment, lugs depending from said body for maintaining longitudinal position of the same on a rail, gripper levers pivotally mounted within said body for scissors-like movement and depending therefrom arranged one on each side of a rail, and cams cooperating with said levers for actuating the same for gripping 120 purposes.

7. A rail stop comprising a body adapted to rest on a rail, lever grippers within said body adapted for pivotal and longitudinal movement on a common pivot and having the 125 lower ends thereof depending from said body for gripping a rail, cams within said body adapted to move said levers into and out of gripping position, another cam adapted to move said levers upwardly when in gripping 130

engagement with the rail for increasing the gripping effect of same, and means for actuating said cams.

8. A car stop having means for gripping a rail web to secure said stop thereon, said means including gripper levers mounted in said body for scissors-like action, means for closing said levers against a rail and means having toggle-like action for maintaining said levers in gripping position against the rail.

9. A car stop having a body member and a pair of gripper levers carried thereby for clamping a rail, said levers being mounted for scissors-like action, a three part cam having two parts cooperating with said levers for spreading and contracting the same, and a third part effective when said levers are pinching a rail to move said levers longitudinally, said cams being carried on a common shaft, and a handle for rotating said shaft.

10. A rail stop, including a body and levers adapted to pinch a rail, cams within said body for causing said pinching action, means for actuating said cams, and another

cam operable by said same means for maintaining said levers in pinching position.

11. In a device of the class described, in combination, a pair of levers, said levers being movably mounted crosswise on a common pivot, cams cooperating with the upper ends of said levers for moving the same to cause the lower ends thereof to grip a rail and means for actuating said cams. 35

12. In a device of the class described, in combination, a pair of levers mounted on a common pivot in crosswise relation and adapted for longitudinal movement thereon, a single member comprising three cam surfaces, two of which are arranged to separately cooperate with said levers for causing gripping action thereof, and a third cooperating with both levers for increasing the pinching effect of the same by bodily raising the same after said other cams have moved said levers against a rail web, and means for actuating said cam member. 40 45

Signed at Chicago, Illinois, this 6th day of March, 1922.

RICHARD D. GALLAGHER.
